UNITED STATES PATENT OFFICE

170,706

TOY SAVINGS BANK

Rex V. Lentz, Dallas, Tex.

Application December 24, 1952, Serial No. 22,867

Term of patent 14 years

(Cl. D34—11)

To all whom it may concern:

Be it known that I, Rex V. Lentz, a citizen of the United States, residing at Dallas, in the county of Dallas, and State of Texas, have invented a new, original, and ornamental Design for Toy Savings Bank, of which the following is a specification, reference being had to the accompanying drawings, forming part thereof.

Fig. 1 is a perspective front view of a toy savings bank, showing my new design; and

Fig. 2 is a rear perspective view thereof.

I claim:

The ornamental design for a toy savings bank, as shown.

REX V. LENTZ.
